METHOD OF AND MEANS FOR ADJUSTING AUDION CIRCUITS.

Application filed July 14, 1925. Serial No. 43,633.

My invention relates to audion repeater circuits and in particular to a method of and means for adjusting such circuits to be unidirectional in action.

5 I use the term "audion repeater circuit" to include any electrical network comprising one or more audion tubes so connected that electrical oscillations may be received by an input branch and delivered in amplified or 10 rectified form to an output branch of said circuit. By an audion repeater circuit which is unidirectional in action I mean an audion repeater circuit in which means are provided 15 for diminishing or eliminating effects upon the input circuit terminals due to potential variations in the output branch.

It is well known that the action of audion repeater circuits, and in particular of audion amplifier circuits, is not ordinarily even approximately unidirectional. The absence of unidirectional action is due to a number of causes, prominent among which are the feedback of currents through the inherent audion tube capacities, and the retroaction due 25 to electrostatic coupling between audion stages when a number of such stages are cascaded. In the copending application of Stuart Ballantine, Serial No. 728,708, filed June 17, 1924, are described the precautions 30 which it is necessary to take in order to make an audion repeater stage practically unidirectional in action.

There are a number of circuits capable of providing unidirectional action or some approximation thereto. One example of such a circuit is that commercially known as the neutrodyne. Another example of such a circuit is that shown in Figure I. In all circuits of this type it is customary to provide certain fixed circuit elements and one or more variable circuit elements, and to adjust said variable element or elements to provide the desired unidirectional effect. This adjustment is usually a manufacturer's adjustment which is necessary because of commercial variations in the circuit elements and audion tubes. If the circuit is of the Wheatstone bridge class, in which input and output branches form conjugate arms of a bridge, this process of adjustment usually comprises balancing the bridge. My invention concerns such adjustment of circuit elements of an audion repeater circuit which is

capable of being made unidirectional in action, and it comprises adjusting such circuit 55 elements under the operating conditions of the audion repeater circuit.

Referring now to the drawings, Fig. I is a circuit diagram of an audion amplifier stage which may be made unidirectional in 60 action. Fig. II is a diagrammatic representation of apparatus arranged according to my invention. Fig. III is an alternative arrangement of apparatus according to my 65 invention.

I shall first describe the circuit of Fig. I. In this circuit the impedance network of the audion amplifier stage is arranged in the form of an alternating current Wheatstone bridge in which the input circuit of the amplifier stage and the output circuit of the 70 amplifier stage, which coincides with the output circuit of the audion tube, form conjugate arms. These circuits are thus electrically isolated from one another when the bridge is balanced, and potential variations in the output circuit impedance are prevented from affecting the input circuit terminals. This circuit is disclosed and claimed in an application of Stuart Ballantine, filed 75 April 3, 1923, Serial No. 629,702.

One balancing arm of the Wheatstone bridge is the inherent capacity of the audion tube represented by the dotted lines at C_m . Another balancing arm is the capacity C_e 85 between the grid and filament of the tube. This capacity may be the inherent grid-filament capacity of the tube, as represented at C_g by the dotted lines, or it may be this inherent tube capacity in parallel with an external capacity here shown at C_i for the sake of generality. The third arm of the bridge is the portion L_a of the coil L_2 and the fourth arm is composed of inductances L_b and L_3 and the mutual inductance M_{23} . 90 The lower terminal 2 of the input circuit is brought by means of the mutual inductance M_{23} to the same alternating current potential as an intermediate point X in the plate circuit impedance. 95

100 G and 2 are the input terminals of the amplifier stage and the remaining pair of conjugate terminals of the Wheatstone bridge are the points P and F. These points are, therefore, possible output terminals of the stage. I find it convenient, however, in cases

where a tuned output circuit is desirable, to provide this circuit as an extra resonant mesh comprising coil L_0 and condenser C_0 , which is coupled to the whole of the coil L_2 , 5 through mutual inductance M_{20} . The output-circuit load then has the nature of the parallel impedance of this tuned circuit and it is immaterial for the purpose of my invention whether I use the points P and F or the terminals of the coil L_0 as output terminals. It is common practice, however, when such a stage is coupled to a succeeding stage, 10 to employ as output terminals the points so designated in Fig. 1.

15 In order to render such an amplifier stage susceptible of adjustment to be unidirectional in action, the circuital restrictions enumerated in the above mentioned co-pending application, Serial No. 728,708, of Stuart 20 Ballantine should be observed. This amplifier stage forms no part, however, of the present invention. It has been described here as a typical form of circuit to the adjustment of which my invention is applicable. 25

It is customary in the above circuit to make C_1 the variable element, by the adjustment of which the Wheatstone bridge is balanced. It has hitherto been common practice to 30 make this adjustment, or the equivalent adjustment in circuits of other types, when the normal space currents of the audion or audions are not present. That is, the audion or audions have not been in the normal 35 operating condition when such adjustments were made. My investigations have disclosed in certain widely-used commercial audions, when the space currents are flowing, a change in the electrostatic capacity 40 between the grid and plate electrodes of as much as 50 percent of its value when the tube is cold; but prior to my invention no process for positively ascertaining the condition of balance when the space currents 45 are flowing has been available. This results in an unbalance or inaccurate adjustment when the tube is operating. This unbalance has hitherto been neglected and has consequently resulted in regenerative or retro- 50 active effects. In the case of a circuit which is capable of being completely balanced such complete balance has therefore not hitherto been obtained, while in the case of a circuit which can at best only be neutralized 55 or compensated for certain frequencies this neutralization or compensation has hitherto fallen short of the optimum.

My method of ascertaining when the proper circuit adjustment is obtained comprises 60 in general impressing an oscillatory or alternating voltage upon the output branch of the audion repeater circuit. In all previous methods of adjustment the voltage has been impressed upon the input branch of the circuit, thereby rendering it impossible to de-

tect the transmission of currents through the balancing network unless the space currents were absent, because of the forward or relay action of the audion space currents which transmitted the input currents to the 70 output branch in amplified form and thus obscured the currents transmitted through the balancing network. But when the driving voltage is impressed upon the output branch in accordance with my invention 75 the adjustments may be made as above described, with the audion filament heated to its normal temperature, with the normal B- battery potential applied to the plate, and with the normal grid bias, that is, with all 80 the normal space currents flowing. This arises from the fact that there is no appreciable backward action from the output branch upon the input branch through the agency of the audion space currents. The 85 only backward action which can occur is that through the audion capacities and through the balancing network, and it is the purpose of the adjustment to limit or suppress such action. 90

A further step in my process comprises connecting across the input terminals or at some convenient point in the input branch of the circuit a detecting or indicating means, to ascertain when the desired adjustment has been made. For instance, I may so adjust the circuit that a null point is shown by the indicating device, which indicates a complete suppression of retroactive currents and complete unidirectional 100 action of the circuit; or I may so adjust it that a desired response of any predetermined character is obtained. 105

It should be understood that the above described circuit and method of adjustment 110 are merely typical of one application of my invention, which is in no way limited to this particular circuit or means of balancing the bridge. For example, the Wheatstone bridge in the above circuit might have as 115 its variable element the mutual inductance M_{20} . My invention is equally applicable to the neutrodyne type of circuit above referred to. I believe myself the first to have successfully adjusted audion repeater circuits, under operating conditions, to be unidirectional in action. 120

In Fig. II, I have shown diagrammatically an arrangement of apparatus for carrying out this adjustment. A shielded receiver 120 1 is connected across the input terminals of the audion repeater circuit 2 which is being adjusted. A shielded radio frequency oscillator and modulator 3 is connected across the output terminals of the repeater circuit 125 2. Telephones or other indicating means are connected to the receiver 1. Modulated radio frequency oscillations of any desired frequency are thus impressed backward through the audion repeater circuit which 130

is adjusted until the desired response or freedom from response is given by the indicating means.

An alternative arrangement is shown in Fig. III, in which 1 is a shielded receiver connected to telephones as in Fig. II, and in which 3 is a shielded radio frequency oscillator. Instead of modulating this oscillator as in the previous arrangement, I employ a separate heterodyne oscillator to modulate the oscillations after they have passed through the audion repeater circuit.

My invention is not confined to a radio frequency balance. I may impress oscillations of any suitable frequency backwards through the circuit which is to be adjusted. The circuit may thus be balanced at any frequency for which it is designed, including audio frequencies and also intermediate frequencies.

Any oscillator capable of producing oscillations over the desired frequency range is suitable for use at 3. I have used an audion oscillator with an inductively coupled oscillation circuit. I may employ any form of receiver, but have found satisfactory one having a detector and two stages of audio amplification working into telephones. It is of the utmost importance for the best results that both the oscillator and the receiver together with all their batteries should be thoroughly shielded so that there may be no direct action between them. Thus any response obtained in the receiver is necessarily due to oscillations forced backward through the audion repeater circuit which is being adjusted.

Arrangements other than those shown in Figs. II and III will occur to those skilled in the art. For example, the modulation may be supplied by an antenna circuit receiving oscillations from a separate source. If an indicating means other than telephones is used in the process of obtaining a balance at radio frequencies, it may be unnecessary to modulate the radio frequency oscillations. Such would be the case if a galvanometer were employed.

It should be understood that my invention is not limited to the adjustment of a single audion stage but may be applied to the adjustment of any audion repeater circuit comprising one or more audion tubes, and that either a separate adjustment of each stage or a simultaneous adjustment of all the stages falls within the scope of my invention. Moreover, it is not limited to any particular circuit or type of circuit and applies broadly to any circuit susceptible of adjustment to produce unidirectional action.

I claim:—

1. In the process of adjusting an audion repeater circuit to limit interaction between the input and output branches of said circuit, the steps which comprise impressing an

oscillatory voltage upon the output branch of said circuit and receiving resulting currents in the input branch of said circuit.

2. The method of adjusting an audion repeater circuit to limit interaction between the input and output branches of said circuit which comprises impressing an oscillatory voltage upon the output branch and varying a reactive element of said circuit to produce currents of a certain predetermined character in the input branch of said circuit. 75

3. The method of neutralizing an audion repeater circuit which comprises impressing an oscillatory voltage upon the output branch and varying a reactive element of said circuit to produce currents of a certain predetermined character in the input branch of said circuit. 80

4. In a method of adjusting an audion repeater circuit to limit interaction between the input and output branches of said circuit the steps which comprise forcing an oscillatory current backward from the output branch to the input branch of said circuit, and detecting said current in the input branch. 85

5. The method of adjusting an audion repeater circuit to be unidirectional in action which comprises impressing radio frequency oscillations upon the output terminals of the circuit, connecting an indicating means across the input terminals of the circuit, and adjusting the circuit until the indicating means gives a desired response. 95

6. The method of adjusting an audion repeater circuit to be unidirectional in action which comprises impressing radio frequency oscillations upon the output terminals of the circuit, connecting an indicating means across the input terminals of the circuit, and adjusting the circuit until the indicating means gives a minimum response. 105

7. The method of adjusting an audion repeater circuit to be unidirectional in action which comprises impressing radio frequency oscillations upon the output terminals of the circuit, connecting an indicating means across the input terminals of the circuit, and adjusting the circuit until the indicating means indicates a null point. 115

8. The method of adjusting an audion repeater circuit to be unidirectional in action which comprises impressing modulated radio frequency oscillations upon the output terminals of the circuit, connecting an indicating means across the input terminals of the circuit, and adjusting the circuit until the indicating means gives a desired response. 120

9. The method of adjusting an audion repeater circuit to be unidirectional in action which comprises impressing radio frequency oscillations upon the output terminals of the circuit, modulating these oscillations, connecting an indicating means across the input 125

terminals of the circuit, and adjusting the circuit until the indicating means gives a desired response.

10. The method of adjusting an audion repeater circuit containing a plurality of audion tubes to be unidirectional in action which comprises impressing an oscillatory voltage upon the output terminals of said circuit, connecting an indicating means across the input terminals of said circuit, and adjusting said circuit until the indicating means gives a response of a predetermined character.

11. The method of adjusting an audion repeater circuit containing a plurality of audion tubes to be unidirectional in action which comprises impressing an oscillatory voltage upon the output terminals of said circuit, connecting an indicating means across the input terminals of said circuit, and adjusting said circuit until the indicating means gives a minimum response.

12. The method of adjusting an audion repeater circuit containing a plurality of audion tubes to be unidirectional in action

which comprises impressing an oscillatory voltage upon the output terminals of said circuit, connecting an indicating means across the input terminals of said circuit, and adjusting said circuit until the indicating means indicates a null point. 30

13. Apparatus for adjusting an audion repeater circuit to be unidirectional in action, comprising, in combination, means for impressing an oscillatory voltage upon the output terminals of said circuit and indicating means connected to the input terminals of said circuit. 35

14. Apparatus for adjusting an audion repeater circuit to be unidirectional in action, comprising, in combination, a radio frequency oscillator connected to the output terminals of said circuit, means for modulating the resulting radio frequency oscillations, and detecting means connected to the input terminals of said circuit. 40 45

In testimony whereof, I affix my signature.

LEWIS M. HULL.
